UNITED STATES PATENT OFFICE

GEORGE PECK CAULKINS, OF DETROIT, MICHIGAN

CABLE-FASTENING DEVICE

Application filed April 26, 1929. Serial No. 358,309.

This invention relates to improvements in cable fasteners, and refers more particularly to fasteners by which two portions of a cable may be securely held relative to one another.

It is an object of the invention to provide a cable fastener by which two portions of a cable may be secured relative to one another after a section of the cable intermediate the two portions has been passed around a fixed member such as a pole, and to so construct the fastener that it may readily be placed in position and tightened by anyone working on a pole or other elevation.

Another object of the invention is to provide such a cable fastener which may be utilized to hold two portions of each of more than one cable, and by which all the cable portions are held by common tightening means which cooperate with the fastener.

With these and other objects and advantages in view, which will become apparent as the specification proceeds, the invention is hereinafter more fully described with the aid of the accompanying drawings, in which:

Figure 1 illustrates a perspective view of the invention holding two portions of a cable, and with a section of the cable intermediate the two portions around a pole.

Figure 2 shows a side elevation of the invention.

Figure 3 is a plan view of the fastener in open position.

Figure 4 shows a modified construction, and

Figure 5 is a view of one half of the fastener shown in Figure 4 with the serrations or corrugations arranged transversely.

Figure 6 is a reduced sized view of a further modification in construction.

Referring to the drawings, more particularly to Figures 1, 2 and 3 thereof, 1 designates a pole around which a cable 2 is passed, and 3 indicates a fastener which consists of two portions 3^a and 3^b. In the usual form of construction these two portions 3^a and 3^b are pivotally connected by a hinge pin 4, and have, towards their other extremities, openings 5 therethrough sub-

stantially at right angles to the axis of the pin 4. One of the sections 3^a is also usually provided with a recess 7 on its outer side to receive the head of a bolt 6 and hold the latter against rotation when the nut 6^a is being tightened.

Transversely of the adjacent sides of the fastener portions 3^a and 3^b opposed substantially semi-circular recesses 8 and 8^a respectively are provided. In these recesses 60 serrations or corrugations 9 and 9^a are formed which are generally spirally directed to conform to the normal spiral winding of a cable as indicated at Figure 3, though, when desired, these serrations or 65 corrugations may be otherwise directed.

When the fastener portion 3^a is moved into open position as indicated in Figures 2 and 3, portions of the cable 2 are placed in the recesses 8^a of the fastener portion 3^b, 70 and then the fastener portion 3^a is moved into closed position so that the recesses 8 overlie the recesses 8^a. The bolt 6 is placed through the openings 5 and the nut 6^a tightened. When this is done the serrations or 75 corrugations 9 and 9^a engage the cable 2, take into the periphery of the latter, and hold it positively against independent movement. It can be clearly seen that this simple operation can be readily accomplished by 80 one man.

In the construction shown in Figures 4 and 5, the fastener portions 3^c and 3^d are provided at both ends with bolt holes 10 for the passage of bolts 11 by which they are held together. Moreover in this instance the fastener portions are each provided with four transverse substantially semi-circular recesses 8^b and 8^c so that two portions of each of two cables 2^a and 2^b may be held 90 thereby. In this instance it is usual to remove one of the bolts 11 and loosen the other sufficiently for the upper fastener portion 3^c to be turned relative to the other fastener portion 3^d so that the portions of the cables 2^a and 2^b may be placed in their respective recesses 8^b in the fastener portion 3^c. The other fastener portion 3^d is then turned so that the second bolt 11 may be passed through both fastener portions, the nuts 11^a 100

are then tightened on the bolts and the cable portions are firmly held. In some cases it is preferable to utilize transverse corrugations or serrations as shown at 9^b in Figure 5, though obviously they may be directed to suit the form of cable to be held.

Figure 6 shows a further modification wherein the fastener portions 3^e and 3^f are provided with openings 10^a towards their extremities for the passage of bolts 11^a, and intermediate apertures 10^b for the passage of a bolt 11^b between the pairs of recesses 18 and 18^a and the pairs of recesses 19 and 19^a. When larger cables are to be supported this form of construction may advantageously be employed.

While in the foregoing the preferred embodiments of the invention have been described and shown, it is understood that these constructions are susceptible to such further alterations and modifications as fall within the scope of the appended claims.

What I claim as my invention and desire to secure by Letters Patent is:

25 1. A cable fastener consisting of two fastener portions pivotally connected to one another, a plurality of recesses formed in the adjacent sides of each of said fastener portions, means for holding said fastener portions together towards their extremities remote from their pivotal connection, and said recesses having serrations or corrugations therein adapted to engage the peripheries of cables which extend therethrough, said serrated or corrugated recesses being adapted to grip two portions of each of at least one cable and hold said portions relative to one another.

40 2. A cable fastener consisting of two fastener portions pivotally connected to one another, a plurality of recesses formed in the adjacent sides of said fastener portions substantially parallel with their pivotal axis, said portions having openings therethrough substantially at right angles to their pivotal axis, and fastening means taking through said openings, said recesses being adapted to engage two portions of at least one cable and hold said portions relative to one another.

45 3. A cable fastener consisting of two fastener portions pivotally connected to one another, a plurality of recesses formed in the adjacent sides of said fastener portions substantially parallel with their pivotal axis, said portions having openings therethrough substantially at right angles to their pivotal axis and towards their extremities remote from said pivotal axis, fastening means taking through said openings, said recesses having serrations or corrugations formed therein so directed as to conform to the winding of cable portions adapted to be placed in said recesses, so that the peripheries of two cable

portions are positively held relative to one another when said fastener portions are held together by their fastening means.

GEORGE PECK CAULKINS.
